UNITED STATES PATENT OFFICE.

EARL G. CHASE, OF SMETHPORT, PENNSYLVANIA.

GLASS-HANDLING APPARATUS.

1,414,547.

Specification of Letters Patent. Patented May 2, 1922.

Application filed December 12, 1919. Serial No. 344,381.

To all whom it may concern:

Be it known that I, EARL G. CHASE, citizen of the United States, residing at Smethport, in the county of McKean and State of Pennsylvania, have invented certain new and useful Improvements in Glass-Handling Apparatus, of which the following is a specification.

This invention relates to glass apparatus 10 and more particularly to an improved apparatus for handling glass cylinders prior to and during the capping and cracking operations and the general object of the invention is to provide a glass horse by the employment of which the taking down, capping, and cracking of glass cylinders may be accomplished with great facility and without the usual likelihood of breaking of the cylinder with the attendant danger to the workers 20 men employed in performing these operations.

At the present time, in taking down glass cylinders, it is customary to proceed in either one of two ways. The more common way is 25 by the employment of mechanical contrivances especially designed for performing this operation but which are more or less complicated and therefore expensive. Where such contrivances are not employed, the cylinders are taken down by hand but this latter method of procedure is attended by danger to the workmen through breakage of the cylinders and furthermore, by it the work 30 cannot be performed as rapidly as might be desired. It is therefore one object of the present invention to provide a means whereby such cylinders may be readily taken down without any particular liability of injury to the workmen and at the same time without 35 the necessity of employing complicated mechanical devices for performing this task.

It not infrequently happens in the drawing of glass cylinders, in the manufacture of window glass, that the cylinders will deviate 40 somewhat from a true cylindrical form so that if, after being taken down they were disposed to rest upon a substantially rigid horse, some portions of their lengths would be spaced above the saddles of the horse thus 45 imposing a strain upon the cylinders. With the object in view of overcoming this disadvantage and in an attempt to provide a more or less continuous and even support for all 50 portions of the length of a cylinder regarding less of any distorted form which it might

have as a result of the drawing operation, glass horses are constructed with spring supported or yieldable saddles so that when a cylinder is taken down and laid upon the horse all of the saddles will be supported 60 by their respective springs in contact or engagement with the under side of the cylinder. While, by the employment of a horse of this construction, the cylinder while at a state of rest will be practically relieved of 65 the strains to which it would otherwise be subjected because of deviations from a true cylindrical form and the lack of support at points in its length where such support should be provided, nevertheless a horse of 70 this construction presents serious disadvantages when employed during the capping operation. As the saddles of such a horse are supported by springs, these springs of course 75 exert an upward thrust upon the saddles, the springs being placed under compression through the weight of the cylinder. As a consequence when the cylinder is capped it not infrequently happens, and particularly 80 if the cylinder is somewhat deformed, that as it is circumferentially cracked, it will fracture at the capping off point due to the difference in weight between the two portions of the cylinder into which its length is 85 to be divided and the consequent tendency of the spring saddles supporting the lighter portion of the cylinder to thrust this portion upwardly above the position of the other and heavier portion of the cylinder. This 90 fracture of the cylinder is even more likely to occur where the cylinder deviates somewhat from a true cylindrical form and where by reason of this fact some of the spring supported saddles are depressed and their 95 springs placed under tension to a greater degree than adjacent ones. It is therefore another important object of the present invention to provide a glass horse so constructed that all portions of the length of a cylinder taken down and disposed upon the horse 100 will be afforded equal support whether the cylinder be of true cylindrical form or somewhat distorted as a result of the drawing operation. Incidentally the invention contemplates the provision of saddles of such construction that they will more or less closely 105 and snugly conform to the shape of the under side of the cylinder and thus support the cylinder in a more stable manner than is the case where wooden saddles are employed. 110

Also in this respect the invention has as its object to provide saddles for supporting the horse, which saddles will not exert any strain upon the cylinder but will on the other hand afford it uniform support throughout its length so that the capping off operation may be performed at any desired points in the length of the cylinder without any likelihood whatsoever of the cylinder being fractured through any uneven pressure or tension exerted upon it by the saddles.

It is a well recognized fact that where horses of the usual construction are employed the cracking operation is rendered more or less tedious and inconvenient to perform and it usually must be postponed until the capping operation has been completed. The present invention, however, has as a further important object to provide a horse so constructed that as each separate portion of the length of the cylinder is capped off, it may be disposed in a position to render it readily accessible to the cracker and so that he may use the cracking iron with the greatest facility and without in any way interfering with the capper or the capping operation.

Ordinarily the saddles of glass horses are constructed of wood or other rigid material and while their upper sides are curved from end to end to receive the cylinder the saddles are not adapted to prevent lateral rolling motion of the cylinder disposed thereon, the arc of curvature of the upper sides of the saddles being usually considerably greater than the arc defined by the circumferential surface of the glass cylinder to be supported thereon. It is therefore a further object of the invention to provide a glass horse with flexible saddles which will automatically more or less conform to the shape of the under side of a cylinder disposed to rest thereon so that the cylinder will be more securely supported and will be prevented from any lateral rolling motion upon the horse.

In the accompanying drawings:

Figure 1 is a perspective view illustrating the horse embodying the present invention and the manner of using the same in taking down a cylinder;

Fig. 2 is a side elevation of the horse, the view, as in Fig. 1, illustrating the use of the horse in taking down a cylinder and the cylinder being shown in full lines in partly lowered position and dotted lines in full lowered position resting upon the horse;

Fig. 3 is a view similar to Fig. 2 but illustrating one section of the horse uncoupled and adjusted to position for the cracking operation;

Fig. 4 is a vertical transverse sectional view taken substantially on the line 4—4 of Fig. 2;

Fig. 5 is a plan view of the truck of one

of the sections of the horse, the saddle supporting platform being shown in dotted lines;

Fig. 6 is a detail vertical sectional view taken substantially on the line 6—6 of 70 Fig. 1.

In the drawings, the glass furnace is indicated in general by the numeral 1 and embodies, of course, the usual drawing pot or well from which the molten glass is to be drawn in the form of a cylinder. As is usual in glass factories, an overhead track 2 is arranged to extend above the furnace and forwardly therefrom, and the usual trolley 3 is mounted to travel upon this track, the travel of the trolley backwardly and forwardly along the track being controlled by a suitable motor 4 arranged upon the usual platform 5 at one end of the track, the circuits controlling the motor being under the control of an attendant who has this duty to perform. The numeral 6 indicates in general the usual cage which houses the blower and from which leads the blow pipe 7 provided at its end with the bait 8, the cage 6 being suspended from the trolley 3 by means of a cable 9 which may be taken up or paid out so as to gradually elevate the cage 6 during the drawing operation and so as to lower the said cage as the drawn cylinder is being taken down. This cable 9 is taken up and paid out through operation of the motor 4 in the usual manner and as the apparatus thus far described is that ordinarily found in glass factories, a detailed illustration and description thereof is deemed unnecessary.

The horse embodying the present invention is not a stationary one but on the other hand is supported for back and forth travel upon track rails 10 which extend forwardly a suitable distance from the front of the furnace 1. The horse comprises a plurality of coupled sections and inasmuch as these sections are of counterpart construction, a description of one will suffice for all. Each section of the horse, indicated in general by the numeral 11, comprises a truck body 12 mounted upon wheels 13 which travel upon the track rails 10, the truck body being flat and substantially rectangular and having its upper surface located above the upper sides of the wheels 13 as clearly shown in Fig. 4 of the drawings. A king pin 14 is mounted at the center of the upper side of the truck body 12 and the said body is provided, concentric to this pin with an annular series of anti-friction rollers or other similar bearing elements 15. Each section of the horse further comprises a platform 16 which supports the saddles and this platform is preferably rectangular and of substantially the same dimensions as the truck body 12 and is provided centrally with an opening or bearing 17 receiving the king 130

pin 14 in the manner clearly shown in Fig. 4 of the drawings, the platform resting at its under side upon the anti-friction elements 15 and being in this manner supported upon the truck body for turning movement in a horizontal plane. It is, of course, preferable to provide anti-friction bearing elements between the truck body and platform so that the platform may be 5 more readily rotated about the king pin but the particular mounting shown in the drawings is to be considered merely as illustrative of the rotatable mounting of the platform and it will be understood that this 10 structure may be modified in many ways and that in fact any suitable means might be provided for rotatably mounting the platform upon the truck body, the inventive idea residing in the rotatable mounting of 15 the platform rather than in any specific means whereby it may be so mounted.

A series of uprights 18 is mounted at one side of the platform 16 and a series of uprights 19 is mounted at the opposite side 25 of the said platform and these uprights may be varied in number as desired. However, the uprights 18 and 19 are equal in number and respective ones are oppositely located or, stated in other words, the uprights are 30 arranged in pairs.

As previously stated the saddles of the horse are flexible and each saddle, indicated in general in the drawings by the numeral 20, consists of a suitable length of cable 35 or other flexible material which is permanently connected at one end as at 21 to the upright 18 of the respective pair of uprights and is lead at its opposite end through the upper end of the companion upright 19. 40 The uprights 19 are preferably tubular as illustrated clearly in Fig. 6 and in order that the last mentioned ends of the respective saddles 20 may be passed therethrough, each upright is formed near its upper end with 45 diametrically oppositely located openings 22, a suitable portion of the length of the flexible saddle being allowed, after being passed through the openings 22, to hang beside the respective upright 19 as indicated by the numeral 23 where it may be grasped and a pull 50 exerted thereon for the purpose of taking up the slack of the saddle or on the other hand the saddle may be slackened by slightly paying out this portion of the said saddle.

55 Above the openings 22, each upright 19 is interiorly threaded as indicated by the numeral 24 and fitted in its upper end is a threaded clamping screw 25 having a concave lower end 26 to provide a circumferential binding edge 27 designed to cooperate 60 with the lower sides of the walls of the openings 22 for the purpose of clamping the cable or other material comprising the saddle 20 and thus holding the same against being 65 drawn through the said opening. Any suit-

able means, such for example as a cross bar 28, may be provided at the upper end of each screw 25 to permit of the screw being rotated to bind or to release the end of the respective saddle.

The several sections of the horse, of which there may be any desired number, are connected together by any desired coupling means indicated by the numeral 29 so that the sections may be readily coupled to one 70 another and readily uncoupled.

The manner of using the horse in the several operations of taking down, capping and cracking the cylinder, will now be described.

The cylinder is first drawn in the usual manner and after having been drawn is carried away from the furnace 1 by causing the trolley 3 to travel along the track 2 in the direction of the platform 5. When the cylinder has been brought, in a suspended vertical position, to a point suitably removed 80

from the furnace, it may be taken down in either one of two ways. One method of procedure is to advance the horse along the track 10 until the foremost saddle of the 90

first section of the horse engages the cylinder near the lower end of the latter. Through the operation of the motor 4, the trolley 3 is then caused to move along the track 2 in the direction of the furnace until the cylinder 95

has assumed approximately an angle of 45° as shown in Fig. 2 of the drawings whereupon the cable 9 is paid out and the cylinder is thus laid upon the saddles of the horse. By the other method of procedure 100

the horse is advanced along the track 10 in the direction of and beyond the platform 5 after the foremost saddle of the forward section of the horse has engaged the lower portion of the cylinder, and at the said time the 105

cable 9 is paid out so that the horse will pass to a position beneath the cylinder as the cylinder is simultaneously lowered onto the horse. It will be evident that by either method the taking down of the cylinder may be accomplished most expeditiously and without any particular likelihood of breakage of the cylinder with consequent injury to the workmen and at the same time I am not required to modify in any way the overhead 110

structure of the apparatus but accomplish the desired results solely through the provision of my horse which is supported for travel beneath the overhead structure.

When the cylinder has been taken down 115 by either of the methods above recited one of the attendants will pass along that side of the horse at which the uprights 19 are located and if he finds that any of the saddles do not snugly and properly engage the under side of the cylinder he will loosen the respective clamping screws 25 and take up the slack in the respective saddles. When this adjustment of the saddles has been completed, all of the saddles will engage the 120

125

130

under side of the cylinder and the cylinder will be afforded uniform support substantially at all points in its length.

The capper now performs his task by capping the cylinder at the intervals between the sections of the horse and as he caps off each portion of the length of the cylinder he will uncouple the section which supports this length and shove the section away from him along the track 10. As the cylinder is afforded uniform support throughout its length there will be no likelihood of fracture of the cylinder as frequently happens where horses having spring supported saddles are employed.

As each section of the cylinder is capped off, the cracker stands ready to perform his task and as the section supporting the cracked off portion of the cylinder is shoved 20 toward him along the track, he will rotate the platform of the section so as to bring the section of the cylinder into position with one end facing him. In this manner the capped off section of the cylinder is supported in such a position as to give the cracker ready access thereto and he can in a most convenient and expeditious manner draw the cracking iron along the inner surface of the cylinder at the lower side thereof 25 in performing the cracking operation.

While the complete horse is illustrated and described as comprising a number of coupled sections, it will be understood that each section in itself constitutes a horse inasmuch as it is provided with its individual 35 saddles and is adapted to support a capped off portion of the length of the drawn cylinder.

Having thus described the invention, what 40 is claimed as new is:

1. A glass horse having a slack flexible saddle, and means whereby the slack of the saddle may be adjusted.
2. In a glass horse, spaced supporting members, a flexible saddle connected to one of the members, and means adjustably connecting the saddle with the other member.
3. In a glass horse, spaced supporting members, a saddle connected with one of 50 said members, the other member having an opening through which an end portion of

the saddle is extended, and means carried by the second mentioned member and adjustable with relation to the opening in the said member to bind the saddle.

4. A glass horse comprising a supporting base, series of uprights mounted at opposite sides of the base, saddles comprising flexible members suspended between corresponding uprights of the two series, the saddles being normally slack, and means whereby the slack of the saddles may be independently adjusted.

5. A glass horse comprising a plurality of sections mounted for travel, a saddle upon 65 each section, and means separably coupling the sections.

6. A glass horse comprising a plurality of sections mounted for travel, means separably coupling the sections, and a plurality 70 of flexible saddles upon each section.

7. A glass horse comprising a plurality of truck bodies supported for travel and separably coupled together, a platform mounted for turning movement upon each truck body, 75 and a saddle supported upon each platform.

8. A glass horse comprising a plurality of wheeled sections, means separably coupling the sections together, and a saddle rotatably mounted upon each section.

9. A glass horse having a horizontally disposed saddle rotatable about a vertical axis.

10. A glass horse having a platform rotatable about a vertical axis, and a horizontally disposed saddle mounted thereon.

11. A glass horse comprising a truck body supported for travel, a platform mounted for turning movement upon the body about a vertical axis, and a horizontally disposed 90 saddle upon the platform.

12. In glass apparatus, in combination with a drawing furnace and an overhead drawing apparatus mounted for travel in a direction toward and from the furnace, a 95 truck mounted for travel in a like direction and in a path beneath the path of travel of the drawing apparatus and having an elevated horse.

In testimony whereof I affix my signature. 100

EARL G. CHASE. [L.S.]
